US0D1025593S

(12) United States Design Patent (10) Patent No.: US D1,025,593 S
(45) Date of Patent:  May 7, 2024

(54) BAG

(71) Applicant: DELVAUX CREATEUR SA, Brussels (BE)

(72) Inventor: Marc Valeanu, Brussels (BE)

() Term: 15 Years

(21) Appl. No.: 35/516,793

(22) Filed: Mar. 21, 2023

(80) Hague Agreement Data

Int. Filing Date: Mar. 21, 2023

Int. Reg. No.: DM/227907

Int. Reg. Date: Mar. 21, 2023

Int. Reg. Pub. Date: Apr. 7, 2023

(30) Foreign Application Priority Data

Sep. 27, 2022 (EM) 009186240

(51) LOC (14) Cl. 03-01

(52) U.S. Cl.

USPC D3/232

(58) Field of Classification Search

USPC D3/232, 233, 242, 243, 244, 245, 246, D3/226, 289

CPC A45C 1/00; A45C 1/02; A45C 3/00; A45C 3/001; A45C 3/06; A45C 7/0059

See application file for complete search history.
